UNITED STATES PATENT OFFICE.

JOHN W. CLARK, OF PHILADELPHIA, PENNSYLVANIA.

RAIL-SPLICING.

1,273,823.

Specification of Letters Patent. Patented July 30, 1918.

Application filed November 22, 1917. Serial No. 203,404.

To all whom it may concern:

Be it known that I, JOHN W. CLARK, a citizen of the United States, residing at Philadelphia, in the county of Philadelphia, 5 State of Pennsylvania, have invented certain new and useful Improvements in Rail-Splittings, of which the following is a description, reference being had to the accompanying drawings, forming a part hereof.

10 My invention relates to splice bars and supports for the meeting ends of railway rails and has for its object to provide a simple and effective splice bar and support for the meeting ends of such rails which 15 will equalize the strength of and distribute the strain on the railway rails at the joints in a manner to prevent pounding by the wheels of the rolling equipment, at such joints. A further object of the invention 20 is to provide a support for the meeting ends of railway rails which will support the rails directly at the meeting ends of the rails as strongly as they are supported at the point of entering the splice bar lock. A further 25 object of the invention is to provide a construction in which the splice bar and the support are so locked together that when the splice bar is bolted in place the support will become practically a part of the rail 30 so that the strain on the support at the lock which is near the ends of the splice bar will be registered at the same time that it is registered at the center of the support or at the meeting ends of the rails so that 35 the rail will receive the direct strain instead of its being received on some supporting means such, for instance, as a cross tie.

With these and other objects hereinafter explained in view my invention consists in 40 the construction and combination of elements hereinafter set forth and particularly pointed out in the claims.

Referring to the drawings—

Figure 1 is a side view of a splice bar and 45 support embodying my invention, in position on the rails.

Fig. 2 is a top plan view of the supporting member shown in Fig. 1.

Fig. 3 is a side view of the supporting 50 member.

Fig. 4 is a cross sectional view on line 4—4 of Fig. 1 and

Fig. 5 is a cross sectional view on line 5—5 of Fig. 1.

55 In the drawings which show a preferred and practical embodiment of the invention

E, E, indicates the two rails the meeting ends of which are to be supported and E' E' indicates the bases of these rails. D, D, indicates the side members of the splice bar, 60 one on each side of the rail having their upper portions adapted to fit tightly between the heads of the rails and their bases E' and to be held in position by the usual bolts E² passing through the rails, the 65 upper portions of the side members being made tapered or wedge shaped in cross section as shown to insure a firm bearing against the head and base of the rail. These side members are provided near their ends 70 with locking supporting portions D', D', extending inward beneath the bases of the rails to receive, between them and the bases of the rails, the ends of the supporting member B, these portions D', D', being provided at their inner ends with upwardly 75 extending lugs A' A' to enter the openings F', F², in the ends of the supporting members.

The supporting member B is of substantially the same length as the side members and formed as shown with relatively thin ends adapted to fit between the bases E', E', of the rails and the portions D', D', of the side members and has in these relatively thin 80 ends openings F' and F² adapted to receive the lugs A', A', to form with these lugs a lock by which the side members and the supporting member will be held against relative movement. Midway between its ends 90 the supporting member is made relatively thick as shown at H, this thickened portion being arranged with its center in line with the plane of the meeting ends of the rails, and to insure proper bearing of this thickened portion against the bases of the rails at the meeting point, the upper face of the supporting member is concaved as shown at 95 G', G², so that the upper face of the supporting member will be in contact with the 100 rail bases E', E', only at their end portions and at its central thickened portion.

The portions D', D', of the side members are relatively short and support the supporting member B only near its ends and being at some distance from the meeting ends of the rails, the strain on the rails at the meeting point is distributed so as to be sustained at points away from the meeting points, the side members and supporting 110 member thus coacting to form a strong effective truss or girder.

Having thus described my invention what I claim is:

1. A splice bar and support for railway rails comprising side members adapted to be secured to the rails and a supporting member having a portion thereof adapted to bear against the bases of the rails at their meeting point, the supporting member having openings therein near its ends and the side members being provided with means for engaging said openings to lock the side members and supporting member against relative movement.
2. A splice bar and support for railway rails comprising side members adapted to be secured to the rails, and a supporting member having its central portion adapted to support the meeting ends of the rails, said supporting member decreasing in thickness from its central portion toward its ends, the side members being provided, at points distant from and not extending to the meeting ends of the rails, with means for supporting the end portions of the supporting member to sustain and distribute the strain on the central portion.
3. A splice bar and support for railway rails comprising side members secured to the rails having portions thereof extending inward beneath the rail bases near their ends only, and a supporting member beneath the

rail bases having its ends resting on the inwardly extending portions of the side members between said inwardly extending portions and the rail bases and having its central portion adapted to support the rail bases at their meeting point, the upper face of the supporting member being concaved between its ends and central portion so as to provide a relatively short central portion opposite the meeting ends of the rails.

4. A splice bar and support for railway rails comprising side members secured to the rails having portions thereof extending inward beneath the rail bases near their ends only, and a supporting member beneath the rail bases having its ends resting on the inwardly extending portions of the side members between said inwardly extending portions and the rail bases and having its central portion adapted to support the rail bases at their meeting point, said inwardly extending portions of the side members being provided with upwardly extending lugs and the supporting member being provided with openings to receive said lugs to lock the supporting member against movement relative to the side members.

In testimony whereof I affix my signature this 19th day of November, 1917.

JOHN W. CLARK.
